N. WATERMAN.

Foot Warmer.

No. 13,859.

Patented Nov. 27, 1855.

UNITED STATES PATENT OFFICE.

NATHANIEL WATERMAN, OF BOSTON, MASSACHUSETTS.

FOOT-WARMER.

Specification of Letters Patent No. 13,859, dated November 27, 1855.

To all whom it may concern:

Be it known that I, NATHANIEL WATERMAN, of Boston, in the county of Suffolk and State of Massachusetts, have invented 5 certain new and useful Improvements in Foot-Warmers; and I do hereby declare the following to be a full, clear, and exact description of the same, reference being had to the accompanying drawings, making a 10 part thereof, in which—

Figure 1, represents a perspective view of one form of foot stove, with the lid raised up. Figs. 2, and 3, represent sections through other forms of stove, all, however, 15 being identical in principle, and varying only in form.

Similar letters where they occur denote like parts in all the figures.

The object of my invention is to make 20 the heat of a foot-warmer, uniform, regular, and of a greater duration; and consists, in placing the hot water reservoir, within an outer case, composed of nonconducting materials, on all of its sides, except 25 that against which the feet are placed, and which latter should be of some good conductor of heat, and cushioned, or covered with carpet, to better retain the heat, as will be described.

30 A, represents a hot water reservoir, provided with a suitably capped opening B, through which it may be readily filled or emptied, and handles C, for lifting it out, or replacing it.

35 D, is a wooden box or case, of such form as is most suitable for its special location, and made larger than the hot water vessel A, within it, leaving a dead space E, all around between the wood, and hot water 40 vessel. The wood and confined air combined being a nonconductor, or bad conductor of heat, prevents its escape at the sides or bottom, though it may circulate around the hot water vessel.

45 The lid F of the outer case, instead of being made of wood, is made of thin sheet metal *a* of any kind, which is a good conductor of heat, and cushioned and covered (as seen in the drawings at G), which not 50 only makes an easy resting place for the feet, but also retains the heat which passes through the plate *a*, into it.

When the foot stove is intended for a bed, the widest side lengthwise is covered

with the metallic plate, cushion, &c., as seen 55 in Fig. 2, and the lid may be entirely of wood. Or instead of wood, any other equally good, non-conductor of heat may be used, the object being to isolate the hot water vessel within a non-conducting case 60 or box, except on that side which is to be cushioned or covered for the feet and to preserve a dead space all around between the hot water vessel, and outer case by which means, the heat from the water is 65 more regularly brought to the feet, and retained for a much longer period, than by the foot stoves heretofore constructed. *b*, are supports of wood, to hold the hot water vessel, away from the sides of the outer 70 case, thus surrounding the hot water box on all sides but one, with two nonconducting agents viz: confined air and wood—the confined air between the water box and conducting metallic plate, prevents the heat 75 from passing too fast through the plate and cushion to the feet, making them pleasantly warm, but not too hot, as all other foot warmers do, and which is known to be injurious.

The novelty and utility of the invention, consist in the air space all around the water box, and the metallic plate at a distance from it, on the side from which the heat is taken, and its capability of dispensing its 85 heat, a very long time, and at a low and even temperature.

Having thus fully described the nature of my invention I would state that I am aware, hot water has been used for heating 90 a foot-warmer, and that foot warmers have been cushioned or covered by carpet, &c. This I do not claim, but

What I do claim as new and desire to secure by Letters Patent, is—

Placing the hot water vessel within a case made of wood except on that side on which the feet are to rest, which side is made of thin sheet metal, and cushioned and covered as herein set forth—the whole being for the purpose of retaining the heat longer, and giving it out more regularly to the feet, as described.

NATHANIEL WATERMAN.
